Fig. 6.

13 Inventor: Charles J. Truiri
By Cheever & Cox Attn's.

UNITED STATES PATENT OFFICE.

CHARLES J. IRWIN, OF CHICAGO, ILLINOIS, ASSIGNOR TO ILLINOIS TOOL WORKS, OF CHICAGO, ILLINOIS, A CORPORATION OF ILLINOIS.

TRUING DEVICE FOR GRINDING WHEELS.

Application filed March 2, 1923. Serial No. 622,275.

My invention relates to truing devices for grinding wheels, grinding points and the like, and the object of the invention is to provide a convenient apparatus which will permit of various adjustments and make it possible to produce a variety of contours in the article to be trued or dressed. It is my purpose to provide a compact and substantially unitary structure capable of producing accurate work and configurating abrasive elements of various shapes and sizes. Another object is to render it easily possible to reproduce, if desired, any given angle. In connection with this last object it will be understood that it is common practice to employ grinding wheels to work on hobs and cutters and other pieces of work where the surface to be ground must lie accurately at a definite angle. In order to effect this it is necessary that the acting surface of the grinding elements must lie at a definite angle. One of my objects is to make it possible, after the proper angle for truing the grinding element has once been determined, to reproduce this angle as many times as desired without requiring a resetting of the frame work of the apparatus. As a result of this feature of the invention different grinding wheels may be introduced into the apparatus one after the other and the same angle reproduced in every specimen without requiring a new angular adjustment each time. I accomplish my objects by the mechanism illustrated in the accompanying drawings in which

Figure 1 is a top plan view of the apparatus as a whole.

Figure 2 is an elevation looking from the front of Figure 1.

Figure 3 is an enlarged sectional view taken on the irregular line 3-3 Figure 6.

Figure 4 is an enlarged sectional view taken on the line 4-4 Figure 6.

Figure 5 is a sectional detail view on the irregular line 5-5 Figure 6.

Figure 6 is an enlarged plan view similar to Figure 1 but showing certain of the parts in axial section.

Like numerals denote like parts throughout the several views.

According to the illustrated design there is a pedestal 1 which forms a support for a shaft 2, which is held in position by a cap 4. The cap is held in place by wing nuts 6 which screw onto studs 8 which rise from

the pedestal and project up through the cap. The cap thus forms a clamp which when tightened will prevent the shaft 2 from rotating about its axis. By loosening the clamp the shaft may be adjusted to any desired angular position.

A frame 10 is secured to the projecting ends of shaft 2 and is held rigid on it by pins 12 or other appropriate means. This frame has a split hub 14 adapted to support the casing 16 of a spindle bearing. Hub 14 is clamped onto the spindle casing by a clamping screw 18 and nut 19. By backing off the nut the hub will spring open far enough to permit casing 16 to be shifted longitudinally for adjustment purposes. A spindle 20 is journaled in casing 18 and at one end has attached to it a grinding wheel 22. This particular grinding wheel is shown in frusto-conical form suitable for grinding a hob 24 indicated in dotted lines at the left of Figure 6. It will be understood, however, that the form of the grinding element upon which my device may operate may be varied. Spindle 20 is driven in any suitable manner, for example, sheave 26 and belt 28.

Now referring more particularly to the elements by which the actual grinding is effected; a dressing "point" 30 (which in practice usually consists of a small pin with a diamond fragment mounted in it) is mounted in a bar 32 which has a pin 34 secured to its rear end. This dressing point contacts the grinding wheel at a point which is approximately diametrically opposite to the point of contact of the grinding wheel with the hob. One advantage of this is that the construction is thus more compact and also the dressing point may contact the grinding wheel at the same time that the latter is in contact with the hob. The hob does not have to be removed before the truing can take place. The pin is arranged obliquely to its line of travel, that is, obliquely to the temple 48, hereinafter mentioned, and consequently it is oblique to the line of contact of the dressing point on the grinding wheel. As a result, a sharp corner of the diamond or dressing point may always be presented to the grinding wheel by rotating the pin on its axis to a fresh angular position when the diamond has become worn. The bar 32 fits slidingly in a channel 36 formed in the side of a block 38 shown in vertical section in Figure 5. This block forms a housing for

60

the bar and permits the latter to slide freely in it both longitudinally and laterally. The side of the channel is closed by a plate 40 which is screwed or otherwise secured to the side of the housing. The rear end of the housing 38 has slots 42 above and below the channel. These are arranged longitudinally in the block and form guides for pin 34. It will be evident that by sliding the pin in the slots 42, the bar 32 will be moved longitudinally.

This sliding movement of the pin is accomplished by means of a lever 44 which is fulcrumed on a pin 46 secured in housing 38. Said lever is bifurcated at its inner end to engage pin 34, as well illustrated in Figure 6. By rotating the lever about its pivot the pin 34 will slide longitudinally in the slots 42.

20 The diamond point is held to its work by a templet 48 which engages a contactor or wearing pin 50 screwed into the back of arm 32. The working edge of the templet (which of course may have various configurations) determines the final configuration of the work. The wearing pin is at all times held in contact with the working edge of the templet by means of a leaf spring 52 which is mounted on the inner side of plate 40 and presses against the side of arm 32.

25 Templet 48 is slidably mounted in housing 38 at the side of arm 32. According to the present design the templet consists of a comparatively thin bar of metal as well shown, for example, in Figure 5. The housing has a shallow channel 54 for accommodating it. The templet has a slot 56 within which is a coiled compression spring 58. This spring is contained in a cylindrical socket 60 in housing 38 as clearly shown in Figure 4. The arrangement is such that the spring constantly urges the templet toward the rear end of the housing (that is, toward the right, Figure 4).

45 The rear edge of the templet is beveled and is engaged by an adjusting screw 62 having a knurled head 64 and lock nut 66. The latter abuts the rear end of the housing. On account of the beveling of the rear end

50 of the templet the action of spring 58 is to constantly urge the templet toward the right Figures 5 and 6 (that is, toward the bottom of the slot in which it is slidably mounted).

55 By adjusting the screw 62 the templet may be adjusted longitudinally, thus enabling any desired portion of the templet to be brought within the zone of action of the wearing pin 50. The templet is backed up by an adjusting screw 68 which is provided with a knurled head 70 and screws within the stem 72 of the housing 38. In the preferred construction, which is well illustrated in Figure 6, the housing 38 and its stem 72 are integral. It will be evident

65 vary the angular position of the templet and thus vary the degree of bevel produced in the work.

The stem 72 is here shown to be cylindrical and is prevented from rotating by arms 76 which form part of the frame 10 and constitute keepers in which housing 38 may slide. Housing 38 and stem 72 constitute what may be termed a sub frame mounted in the main frame 10. Stem 72 is 75 slidable within the housing 74 and its position longitudinally is determined by a feed screw 77 which works in an internally threaded socket 78 in the stem, as best shown in Figure 6. This screw has a collar 80 near its outer end which abuts a plate 82 screwed or otherwise fastened to the rear end of housing 74. At the outer end the screw has a knurled head 84, the hub of which abuts the outer surface of plate 82. Thus when the screw is rotated it will shift the stem 72 longitudinally but will itself be prevented from moving longitudinally.

80 The operation of the mechanism has already been described in detail and it will 90 be sufficient to say that when the parts have been assembled as illustrated in Figures 1 and 6 and elsewhere the spindle 20 will be set rotating at high speed and the diamond point will then be moved forward and back 95 along the surface of the rapidly rotating grinding wheel by oscillating the lever 44 back and forth about its axis 46. The wearing pin 50 will, of course, slide along the working edge of the templet 48, and the 100 path of the diamond point will be a counterpart of that portion of the working edge of the templet over which the working pin travels during the course of the movement. As the grinding surface wears away the 105 diamond point may be made to follow it up by rotating the feed screw 76. This will advance the parts without changing the degree of bevel in the work. In fact the 110 whole housing 38 may be removed from the frame and then replaced without changing any adjustment.

115 While my device may constitute a separate and individual truing mechanism, I employ it in practice in the form of an attachment 115 to a hob grinding machine such, for example, as is shown in my companion application filed May 3, 1923, Serial No. 636,323. In the mechanism there illustrated the pedestal 1 constitutes the tool post of the machine. 120 It will be evident that my mechanism is exceedingly simple and reliable. As the entire framework is here shown as being in the form of a single piece, the structure remains rigid and reliable at all times. By 125 employing it in connection with the tool post of a hob grinder my apparatus may be placed and withdrawn as a unit. It is possible to make very fine adjustments for it will be evident that where a templet is employed 130

in which the working edge is straight the taper may be accurately controlled by means of the adjusting screw 68 in connection with the adjusting screw 62. These adjustments 5 need not be disturbed when the apparatus is placed in or taken from the hob grinding machine nor need they be disturbed when the feed screw 76 is rotated in one direction or another to bring the pressing point 10 toward or from the work. After the adjustment has once been made the movement required of the operator is quite simple, for all he has to do is to oscillate the lever 44 back and forth about its axis. The spring 15 52 keeps the wearing pin 50 in contact with the templet during the various positions of the latter and also serves to prevent the bar 32 from swinging out of contact when the work is not present. The device as an 20 entirely will thus be seen to be both convenient to use and accurate in its work, and capable of maintaining a given angle while one specimen of work is removed and another positioned.

25 It will be observed that the parts are so proportioned and arranged that the grinding wheel and the dressing tool are in line with the axis of the pivotally mounted main frame 10. It will also be observed that the 30 axis of the grinder spindle, the line of movement of the stem 72 and the pivotal axis of the main frame lie substantially in a common plane and are oblique each with respect to the other. It will also be noted that the 35 stem 72 occupies an intermediate position between the axis of the grinder spindle and the pivotal axis of the main frame. Also it will be noted that the contactor 50 is located directly behind the dressing tool 30. These 40 characteristics produce a most compact and simple construction. They also make it possible to bring the dressing tool readily into and out of engagement with the grinding wheel. The necessary movement is very 45 slight and yet the truing mechanism is at all times out of the way of and free from interference with the object to which the grinding wheel is to be applied.

Having thus described my invention, what 50 I claim as new and desire to secure by Letters Patent is:

1. Truing mechanism having a bar, a housing in which said bar is encased, said bar being both longitudinally and laterally 55 movable in the housing, a dressing point projecting from one side of the bar near one end, a pivot near the opposite end of the bar, a templet arranged alongside of and behind the bar fixed relatively thereto during 60 truing, a contactor projecting from the back of the bar directly behind the dressing point, and means mounted on the housing for sliding the bar longitudinally to cause the dressing point to travel over the 65 surface of the grinding wheel to be trued.

2. Truing mechanism having a bar provided with a dressing tool and a contactor at one end thereof, located on opposite sides and substantially in line with each other, a housing in which the bar is freely movable 70 both longitudinally and laterally, a templet extending lengthwise and behind the bar in position to be engaged by the contactor, the end adjacent to the contactor being freely movable in the same plane as the bar, the 75 opposite end of the templet being pivoted at a fixed point thereon on the housing during truing, and means for adjusting the free end of the templet toward and from the contactor.

3. Apparatus of the class described including a frame having a tool holder support by which a grinding tool may be presented to the work to be ground, a dressing tool for dressing the grinder, said dressing tool having a dressing point which contacts the grinding wheel at a point substantially diametrically opposite to the point of contact of the grinding wheel on the work, a support for the dressing tool, said 80 support having a stem which is slidable in said frame to move the dressing tool toward and from the grinder, the line of motion of said support being oblique to the axis of the grinder, and being between the wheel axis and the axis about which the wheel support turns, and adjusting means mounted on the frame and operative upon said stem for moving the stem to acting and non-acting position for moving the dressing tool 90 into and out of contact with the grinder.

4. Truing mechanism having a main frame, a grinding wheel supporting spindle rotatably mounted in said frame, a sub frame a bar provided with a dressing point, said bar being freely slidable in a given plane in said sub frame, a templet backing up said bar, said templet being adjustable in the same plane as the bar for moving the dressing point toward and from the grinding 105 wheel, an adjusting screw for adjusting the templet longitudinally, and a spring for holding the templet in contact with the adjusting screw, the sub frame having a bearing surface and the rear end of the templet 110 being bevelled whereby when engaged by the adjusting screw it is held in contact with the bearing surface in the frame.

5. Truing mechanism having a grinder to be trued, a main frame which is pivotally 115 mounted upon a horizontal axis extending approximately through the grinder, a grinder spindle, a casing in which it is journaled, means forming part of the main frame for holding said casing at an oblique angle to the axis of the main frame approximately in a plane passing through it, a dressing tool having a dressing point for engaging the grinding wheel at a point diametrically opposite to the point of contact of the grinding 120 125 130

- wheel on the work, a sub-frame adjustably mounted in the main frame, a bar for supporting the dressing point, means for guiding the bar relatively to the sub frame, and means for moving the bar longitudinally in the sub-frame at an angle oblique to the axis of the main frame and oblique to the axis of the grinder spindle, and on the opposite side of the main frame axis from the grinder spindle axis.
6. Truing mechanism having a main frame which is pivotally mounted about a horizontal axis, a grinder spindle for supporting the grinder to be dressed, a casing in which the grinder spindle is journaled to rotate on an axis lying approximately in a plane passing through the axis of the main frame, means forming part of the main frame for supporting said casing and holding it at an oblique angle to the axis of the main frame and holding the grinder approximately in line with the axis of the main frame, a dressing tool having a dressing point for engaging the grinding wheel, and a support for holding said dressing point for engaging the grinding wheel, a sub frame adjustably mounted in the main frame, and a support mounted in the sub frame for holding said dressing point in contact with the grinder at a point diametrically opposite to the point of application of the grinder to the work, said sub frame being slidably mounted in the main frame to adjust the dressing point toward and from the grinding wheel, said sub frame being movable rectilinearly in a direction oblique both to the axis of the grinder spindle and the axis of the main frame, and along a line located between the spindle axis and the axis of the main frame.
7. Truing mechanism having a main frame, a spindle for supporting the grinding wheel to be dressed, a casing in which the spindle is journaled, means on the main frame for supporting the casing, a dressing tool, a bar for supporting said tool, a contactor mounted on the bar on the opposite side of and approximately in line with the dressing tool, a templet for controlling said contactor, a sub frame movably mounted in the main frame for supporting the bar and templet and moving the dressing tool toward and from the grinding wheel, and means mounted on the sub frame for moving the bar relatively to it to thereby cause the dressing tool to travel over the surface of the dressing wheel.
8. Means for dressing grinding wheels comprising a main frame in which the grinding wheel is supported, a sub frame mounted in the main frame, a dressing point, a supporting element for the dressing point, a contactor on the supporting element, a templet for backing up the contactor, said templet at one end being movable toward and from the grinding wheel and at the other end slidable longitudinally, and means for adjusting the movable end of the templet toward and away from the contactor for varying the angularity of the path of travel of the dressing point relatively to the axis of the grinding wheel.
9. Means for dressing grinding wheels comprising a main frame in which the grinding wheel is supported, a sub frame movably mounted in the main frame, a dressing point, a supporting element for the dressing point, a contactor on the supporting element, a templet for backing up the contactor, said templet at one end being movable toward and from the grinding wheel and at the other end slidable longitudinally, means for adjusting the movable end of the templet toward and away from the contactor for varying the angularity of the path of travel of the dressing point relatively to the axis of the grinding wheel, and means for moving the sub frame as a whole toward and from the grinding wheel.
10. In a hob grinding machine, a combined grinding and dressing unit having a rigid frame adapted to hold the grinding wheel in contact with the hob, a sub frame mounted in the main frame and adjustable along a line oblique to and in the same plane as the wheel axis and as the axis of the main frame and located between said axes, a bar having a dressing point on the front and a contactor fastened to the back, a templet behind said bar for guiding the contactor, and means for reciprocating the bar to slide the contactor along the templet.

In witness whereof, I have hereunto subscribed my name.

CHARLES J. IRWIN.
